UNITED STATES PATENT OFFICE.

MIKE J. FURLONG, OF TRENTON, MISSOURI.

DOOR.

1,169,143.

Specification of Letters Patent. Patented Jan. 25, 1916.

Application filed March 4, 1915. Serial No. 12,178.

To all whom it may concern:

Be it known that I, MIKE J. FURLONG, a citizen of the United States, and a resident of the city of Trenton, in the county of 5 Grundy and State of Missouri, have invented certain new and useful Improvements in Doors; and I do hereby declare that the following is a full, clear, and exact description of the same, reference being had 10 to the accompanying drawings, and to the numerals of reference marked thereon, which form a part of this specification.

Oftentimes in small buildings, particularly private garages, it is desirable to use 15 all the space available, but this is not always possible owing to the fact that in some instances conditions require the doors of the building to be hung in such a manner as to swing inwardly. Consequently, that portion 20 of the interior of the building swept through by the door in its movement must necessarily remain unoccupied, in order to permit opening and closing of the door. Of course, in some instances, sliding doors have 25 been provided and, where adaptable, have proved satisfactory, but sometimes the width of the doorway is so great that there is not sufficient space for the large sliding doors then required, to move into an open 30 position.

It is an object therefore of this invention to construct an inwardly opening sliding door which may swing from a closed position over a doorway in one wall to an open 35 position adjacent another wall of the building, thus affording an unobstructed opening through the doorway.

It is also an object of this invention to construct a slideable door supported upon 40 suitable tracks mounted at an angle to one another on adjacent walls at the corner of a building, permitting the door to swing from a closed position to an open position, the door when in closed position being disposed 45 over an opening in one wall and in open position being disposed adjacent the other wall, so that free access is had through said doorway.

It is also an important object of this invention to construct a sliding door adapted 50 to operate in a confined space, moving from one wall to another during an opening or closing movement.

It is furthermore an important object of 55 this invention to construct a pivotally mounted slideable door, one end of which is

supported upon a track secured to one wall of a building and the other end of which is secured to a track mounted upon an adjacent wall of the building at the corner thereof, 60 permitting said door to be moved upon said respective tracks from a position over a doorway opening in one wall to a position over the other wall, thus affording an unobstructed passage through the doorway. 65

It is finally an object of this invention to construct an improved type of door movable in a confined space, and when either in fully open or closed position, as the case may be, lying flat against the walls of the building. 70

The invention (in a preferred form) is illustrated in the drawings and hereinafter more fully described.

In the drawings: Figure 1 is a fragmentary interior perspective view of the corner 75 of a building equipped with a door involving the principles of my invention. Fig. 2 is a section taken on line 2—2 of Fig. 1, with the door shown in open position. Fig. 3 is a fragmentary detail section taken on line 80 3—3 of Fig. 1. Fig. 4 is a detail section taken on line 4—4 of Fig. 1. Fig. 5 is a detail section taken on line 5—5 of Fig. 1. Fig. 6 is a detail section taken on line 6—6 of Fig. 2. Fig. 7 is a detail section taken 85 on line 7—7 of Fig. 3. Fig. 8 is an enlarged detail sectional view similar to Fig. 2, of the corner of the building with the door support mounted thereon.

As shown in the drawings, the walls of 90 the building, a corner of which is shown, are denoted respectively by the reference numerals 1 and 2, with the floor designated by the reference numeral 3. The doorway opening is cut in the wall 1, and mounted 95 horizontally thereabove on the inner surface of the wall 1, is a track 4, consisting of a heavy bar of metal, bolted or otherwise secured at its ends to the wall. Intermediate spacing members 5, are provided between 100 said track bar 4, and the wall 1, and bolts extend therethrough to assist in supporting said bar upon the wall. Another flat track bar 6, is bent inwardly at one end and bolted to the wall 2, at the same height thereon as the track 4, on the wall 1, and a plurality of Z-shaped bracket members 7, are secured to said track bar 6, and to the wall 2, to assist in supporting the track bar 105 thereon.

A door, designated by the reference numeral 8, is mounted to move upon said re-

- spective track bars 4 and 6, and for this purpose at one of its ends is provided with a support 9, to which a support 10 is pivotally connected, said bracket 10, having pivoted therein a grooved wheel or roller 11, which tracks upon the bar 4. At the other end of said door 8, another support 12, is provided which, as clearly shown in Figs. 5 and 6, is flanged outwardly from the surface of the door, and pivotally connected thereto is a bracket 13, in which is journaled a grooved wheel 14, which tracks upon the bar 6. Z-shaped brackets 15, are bolted to the wall 1, in a position to engage over the end of the door 8, when the same is in closed position, thus limiting the movement of said door, and also resisting any attempt to thrust the same inwardly by pressure applied on the exterior thereof.
- 20 The operation is as follows: The door as shown in Fig. 1, is illustrated in closed position, and as shown in Fig. 2 is in open position, with an intermediate position thereof illustrated in dotted lines in Fig. 2. In order to open the door from the position shown in Fig. 1, to that illustrated in Fig. 2, it is only necessary to pull the end at which the bracket 13, is attached inwardly, so that the roller therein tracks along the bar 6, and consequently the roller 11, in the pivoted bracket 10, at the other end of the door moves along the bar 4, so that the door not only slides but also swings into a new position, that is, parallel to or adjacent the wall.
- 25 2. Because of the fact that the rail 6 terminates short of the rail 4, it is necessary that the door, in order that it when in closing position, may lie flush with the wall, shall move at its inner end beyond the end of said rail 6, 30 which movement is permitted by the outwardly flanged bracket 12, said construction permitting the roller 14 to remain on the

track 6 while the door 8 will come flush with the wall 1. Although I have not shown any particular locking means associated with the door for the purpose of retaining the same in closed position, it is obvious that the same may be adapted thereto, preferably at the end at which the bracket 13, is connected, in order to resist movement thereof inwardly from the wall 1. Also, if desired, the track bars 4 and 6, respectively, may be inclined in such a manner that the door will roll by gravity into a closed position after having been opened.

55 I am aware that various details of construction may be varied through a wide range without departing from the principles of this invention, and I therefore do not purpose limiting the patent granted otherwise than necessitated by the prior art.

60 I claim as my invention:

65 In a device of the class described, a track secured upon one wall of a building, another track secured on another wall of the building but terminating short of said first track to permit the passage of a roller thereon, a door, a bracket pivoted thereto, a roller journaled in said bracket directly above said door to move upon said first-mentioned track, a support secured at the other end of the door and flanged outwardly therefrom, a bracket pivoted thereto, and a roller journaled in said bracket outside of the vertical line of the door and engaged upon the second track.

70 75

In testimony whereof I have hereunto subscribed my name in the presence of two subscribing witnesses.

MIKE J. FURLONG.
